United States Patent Office.

NORMAN MAXHAM, OF HANCOCK, VERMONT, ASSIGNOR TO HIMSELF AND
C. G. ROBBINS, OF SAME PLACE.

Letters Patent No. 74,841, dated February 25, 1868.

IMPROVEMENT IN HUB AND AXLE.

The Schedule referred to in these Letters Patent and making part of the same.

TO ALL WHOM IT MAY CONCERN:

Be it known that I, NORMAN MAXHAM, of Hancock, in the county of Addison, and State of Vermont, have invented a new and improved Sand-Head; and I do hereby declare that the following is a full, clear, and exact description thereof, which will enable others skilled in the art to make and use the same, reference being had to the accompanying drawings, forming part of this specification.

This invention relates to a new and improved method of constructing apparatus for preventing sand or dirt from working into and injuring the boxes or axles of carriages. It consists of a sand-head attached to the hub, revolving with said hub around the axle, within a cover or box attached to the axle, said cover being provided on the under side of the same with a nick or notch through which sand or dirt caught by the sand-head will fall to the ground. In the accompanying plate of drawings—

Figure 1 represents a central horizontal section of my invention, with the hub and axle also shown in section.

Figure 2 is a plan view of the same, the axle being shown wrong side up, to show the nick or notch in the cover.

Similar letters of reference indicate corresponding parts.

A is the hub; B is the iron axle; B' is the wooden axle; H is a box or cover attached to the axle B'; O is a nick or slot in same; a is a clamp securing wooden axle B' to iron axle B; D is a sand-head attached to hub A; a' are ridges on said head D, a short distance apart, forming in said sand-head D a groove or channel; n is a nut. The hub A and axle B are constructed of the ordinary materials, and in the ordinary way. The hub A is fitted on the axle B, and secured to the same by a nut, n, fitting on a screw-thread on the end of the axle B in the usual way. Upon the inner end of the hub A, and rigidly secured to the same, is a metallic ring or sand-head, D, so arranged as to cover the axle at a little distance from and revolve with the hub around the same within the box H, said ring or said sand-head D forming a part of the hub, and extending in beyond the same a short distance over the axle. Upon the outside of said sand-head D, and near the end of the same, so as with the end of the hub A to form two narrow grooves, are the ridges a', the object of said grooves being to catch any sand or dirt, and prevent the same from working into and injuring the box or axle. Upon the axle B, and so as entirely to cover the sand-head D, and rigidly secured to said axle, is a box or cover, H, the said cover H being in the form of a cup or box with the opening towards the hub A, the other end or bottom being provided with a hole through which passes the axle B, and by which said bottom or end said cover H is fastened to said axle B, the sand-head D extending out beyond the hub A, so as to touch and revolve against the bottom or end of said box H, so as to admit no sand or dirt between said sand-head D and the end of said box H. Said box H is provided on the under side of the same, as shown in the drawing, fig. 2, with a nick or notch, through which the sand caught by the grooves in the sand-head D falls to the ground. The operation is readily seen from the drawing.

Constructed as above described, it constitutes a neat and cheap apparatus for preventing injury to the boxes and axles of carriages from the grinding of sand working in between said axles and said boxes.

I claim as new, and desire to secure by Letters Patent—

The sand-head D, in combination with the hub A and cover H and axle B, substantially as shown and described, and for the purposes set forth.

NORMAN MAXHAM.
